PIVOT

Edmond O. Roy, Franklin, N. H.

Application March 30, 1937, Serial No. 133,916

2 Claims. (Cl. 66—122)

The invention relates to a pivot and more especially to a knitting needle pivot formation.

The primary object of the invention is the provision of a pivot of this character, wherein the same is struck from the body of the knitting needle for swingingly connecting the latch of such needle thereto and spot welding of such pivot is obtainable with dispatch, the pivot in the formation thereof being novel in construction.

Another object of the invention is the provision of a pivot of this character, wherein the same is formed at one side of a slot of a knitting needle and effects a solid pivot for the latch of the needle and in this fashion eliminating the falling out of the latch from the needle or the working loose of the pivot for such latch as well as assuring perfect freedom of the latch of the needle when the latter is in use.

A further object of the invention is the provision of a pivot of this character, which is extremely simple in construction, thoroughly reliable and effective in operation, readily and easily formed, strong, durable, and inexpensive to manufacture.

With these and other objects in view, the invention consists in the features of construction, combination and arrangement of parts as will be hereinafter more fully described, illustrated in the accompanying drawing, which discloses the preferred embodiment of the invention and pointed out in the claims hereunto appended.

In the accompanying drawing:

Figure 1 is a fragmentary side elevation of a knitting needle for a knitting machine showing the pivot constructed in accordance with the invention formed therewith.

Figure 2 is a sectional view on the line 2—2 of Figure 1 looking in the direction of the arrows.

Figure 3 is an enlarged transverse sectional view taken on the line 3—3 of Figure 1 looking in the direction of the arrows.

Similar reference characters indicate corresponding parts throughout the several views in the drawing.

Referring to the drawing in detail, A designates generally a portion of a knitting needle for use

in knitting machines having the usual terminal hook 5 with which coacts a swinging latch 6. Formed in the needle A next to the terminal hook 5 thereof is a longitudinally disposed elongated slot 7 for accommodating the pivotal end 8 of the latch 6 and this slot 7 is offset from the longitudinal center axis of the said needle A thereby effecting a thin side 9 comparable with a relatively thick side 10 with respect to the slot 7.

Punched inwardly from the thick side 10 of the needle A is a solid pivot 11 for the pivot end 8 of the latch 6 when this pivot end is accommodated within the slot 7. This pivot 11 in the form of a lug meets the wall or face of the side 9 confronting the slot 7 while formed in this side 9 aligned with the lug 11 is a recess 12 effecting a shallow web 13 next to the lug 11 at its end 14 so that electric spot welding of the lug with the said web 13 can be effected in the use of a welding tool point. However, the spot welding of the lug 11 may be dispensed with and by the formation of the pivot for the latch 6 there is no possibility of the latch working loose or the dropping of the pivot from the needle A should it be a separate part thereof.

By the punching of the pivot 11 from the side 10, such pivot remains intact with this side of the needle A being integral therewith.

What is claimed is:

1. In a needle of the kind described, a slotted body having a thin and opposite thicker side with respect to the slot therein, a swinging latch accommodated within said slot, and a pivot struck from the thicker side and meeting the thinner side for swingingly supporting the latch.

2. In a needle of the kind described, a slotted body having a thin and opposite thicker side with respect to the slot therein, a swinging latch accommodated within said slot, and a pivot struck from the thicker side and meeting the thinner side for swingingly supporting the latch, the said thin side having a recess extending only partly through the same and aligned with said pivot for spot welding of the latter.
